DES 139

Des. 139

Dow. A. Booth, New York, New York.
Letters Patent Design No 139, dated 24th Feby 1844

The schedule referred to in these Letters Patent and making part of the same.

To all to whom these presents shall come: Be it known, that I, Dow A. Booth, of the City, County, and State of New York, have invented a new and ornamental design for figured silk buttons, and that the following is a full, clear, and exact description thereof, reference being had to the accompanying drawing, making part of this specification.

This design for an ornamental button is composed of two distinct elements or characters which are to be used in con-

102
bination to insure the beauty of the article; these consist, first, in the configuration of the mold or block, having radial indentations thereon, which forms the basis of the button; and second, in winding said block with silk in the manner hereafter described - the beauty and effect of this design being due to these two features which together form the design, without which it cannot be produced.

In the accompanying drawings figures 1, 2, and 3 represent wooden molds cut with different figures all of which radiate from the centre, so that in winding on the silk the threads shall crop each other in the centre represented in figures 4, 5, and 6.

After the threads of silk have been wound on to the mould, where they crop each other in the centre they are secured by a thread which passes through a hole in the centre of the mould, as shown in figures 1, 2, and 3, to prevent the figuring threads from slipping from their appropriate places.

In addition to this mode of figuring, the silk or radially wound covering can be varied in its colors to any extent of shade desired without affecting the general character of the design. It will be obvious from the foregoing that the figures can be changed at pleasure by giving the desired form to the face of the mould, so long as these figures are formed in the face of the mould by depressions and elevations which radiate from a point, whether on the centre of the mould, or eccentric thereto.

What I claim in the above described design as my invention and desire to secure by letters patent is the radially formed ornaments on the face of the mould or block of which the button is formed combined with the mode of winding the covering on the same, substantially as set forth, whether the said covering be of one or more colors.
